United States Patent Office

Des. 183,20
Patented July 15, 195

183,206

TROPHY BASE

Ray E. Dodge and Ada W. Dodge, Miami Beach, Fla.,
assignors to Dodge, Inc., Chicago, Ill., a corporation of
Illinois

Application December 23, 1957, Serial No. 49,017

Term of patent 14 years

(Cl. D29—23)

Fig. 1 is a front elevational view of the trophy base, showing our new design;

Fig. 2 is a side elevational view;

Fig. 3 is a top plan view; and

Fig. 4 is a front perspective view thereof with the base and cover portion being omitted for convenience of illustration.

The dominant feature of our design resides in the portion shown in full lines.

We claim:

The ornamental design for a trophy base, as shown and described.
